UNITED STATES PATENT OFFICE.

GODFREY ENGEL, SR., OF BROOKLYN, NEW YORK, ASSIGNOR TO BUFFALO FOUNDRY & MACHINE CO., OF BUFFALO, NEW YORK, A CORPORATION OF NEW YORK.

CONCENTRATING EVAPORATOR.

Application filed April 17, 1920. Serial No. 374,659.

To all whom it may concern:

Be it known that I, GODFREY ENGEL, Sr., a citizen of the United States, and a resident of Brooklyn, county of Kings, and State of New York, have invented certain new and useful Improvements in Concentrating Evaporators, of which the following is a specification.

My present invention relates to vacuum 10 pans and evaporators of the calandria type.

The objects of the invention are to obtain a maximum of heating surface with a minimum cubic content at the level of the calandria; to promote the circulation and the 15 crystallization; to reduce the time necessary for the complete cycle of operation; to enable the operation at lower temperatures than has been possible heretofore; to increase the capacity and the yield of crystallization; to simplify the structure and to 20 favor the complete discharge of sugar from all surfaces and to provide effective circulation of the steam or heating fluid.

These objects I have accomplished by a 25 novel construction, combination and arrangement of parts, as will be more fully disclosed in the course of the following specification, reference being had to the accompanying drawing, wherein I have illustrated 30 the invention embodied in practical, commercial forms.

In the drawing:

Figure 1 is a vertical part sectional view 35 of a vacuum pan, constructed in accordance with and embodying my invention.

Figure 2 is an enlarged sectional view of the calandria structure, of Figure 1.

Figure 3 is a sectional elevation of a portion 40 of a vacuum pan of modified construction.

Figure 4 is a similar view of another modified form of construction.

The pan shown embodies a shell or casing 5 which differs from the usual structures of 45 this type, in that it is contracted at a point 6 somewhat above the inclined bottom thereof, to provide a heating compartment in the

lower section of the pan of materially reduced cubic capacity.

This throat, or constricted portion of the 50 casing, is shown as produced by inserting a wall section 7 above the bottom of the pan, which is contracted toward its upper end to meet a correspondingly contracted portion 8 at the lower end of the adjoining section 55 of the casing.

The calandria is made up of upper and lower tube sheets 9 and 10 of substantially conical shape, to provide inwardly and downwardly sloping or inclined surfaces, 60 and tubes 11, 12 and 13 between the same. A special feature of these tube sheets is that one of them, the lower one in the present illustration, is of greater diameter than the other, so as to substantially fill up the enlarged space of increased capacity below the contracted portion of the pan. 65

The outer edges of the tube sheets are shown as connected together by the wall section 7 and the inner peripheral portions 70 of the tube sheets are shown as connected together by a down-take tube or plate 14, stepped as indicated at 15 and 16 to take the ends of the shorter length tubes 12 and 13. 75

The tubes are inclined, as indicated, downwardly and outwardly and the outermost tubes 11 are preferably arranged quite close to the outer edges of the tube sheets, so as to provide the maximum of heating surface. 80

The steam is admitted to the calandria through a suitable inlet or inlets 17, provided in the outer wall of the calandria and condensation may be taken off through a drainage pipe or pipes 18. The incondensable gases may be taken off through upper and lower outlets 19 and 20, the upper serving for the escape of the lighter gases and the lower for the heavier gases. This lower outlet may be extended by means of a pipe 90 indicated at 21 to the innermost and lower portion of the calandria.

The outer wall section 7 of the calandria may be slightly enlarged or bulged out-

wardly between the larger and smaller ends thereof substantially as indicated at 22, to provide a steam chest for facilitating circulation of the steam to all of the heating tubes.

5 This invention, it will be seen, provides a maximum of heating surface with a minimum cubic content at the level where the calandria is covered by the syrup, facilitating rapid crystallization and accurate control of the operation.

10 The increase in diameter of the pan above the level of the contracted portion provides for any desired capacity of the pan, so that 15 without affecting the ultimate capacity, a much more efficient operation is attained than has been possible heretofore. As the granulation progresses, more liquor may be admitted up to the desired high level of the apparatus and by reason of the practically uninterrupted inclined surface of the upper tube sheet, the magma may be quickly discharged. The steps 15 and 16 provided for 20 the short length tubes may be inclined substantially parallel with the upper tube sheet, as indicated, so as to prevent the magma from lodging thereon. By arranging the parts as shown, with the tube sheet of larger 25 diameter at the bottom, the greatest heating surface is provided at the lower portion of 30 the calandria and this facilitates and increases the circulation.

35 In the construction shown in Figure 3, the inner peripheries of the tube sheets 9^A and 10^A are connected by a stepped shell 30. The upper tube sheet, as in the previous case, is connected with the casing 5^A. In this case, however, the lower tube sheet 10^A is not connected with the casing, but only 40 with the shell 30. A flange 31 extending from the step of the shell 30 is also connected with the casing. The inlet 17^A, in this case, is connected with the casing between the flange 31 and the upper tube 45 sheet 9^A.

50 In the modification shown in Figure 4, the calandria is of the floating type. In this case, the outer peripheries of the upper and lower tube sheets 9^B and 10^B are connected by a stepped shell 32 which, as in the modification shown in Figure 3, is concentric 55 with the inner shell 14. The inlet 17^B is connected with the inner shell 32 and in this modification the casing 5^B may be cylindrical.

60 By means of this invention there is freedom of circulation and of discharge of the contents and crystallization is effected at low temperatures and high vacuum in the lower part of the apparatus and the process may be completed in one device, instead of being necessarily interdependent upon other vacuum pans.

65 What I claim is:

1. In apparatus of the character described,

a calandria comprising upper and lower inclined tube sheets one of greater diameter than the other, tubes extending between said sheets, a stepped inner wall connecting said sheets, and tubes engaged between the stepped portion of said wall and the tube sheet of greater diameter.

2. In apparatus of the character described, an inclined tube sheet, a tube sheet supported in cooperating relation thereto, a shell connecting the edge portions of said tube sheets and having a stepped portion disposed in opposition to the inclined tube sheet, tubes extending between the tube sheets and other tubes between the inclined tube sheet and the stepped portion of the connecting shell.

3. In apparatus of the character described, an upper tube sheet, an inclined lower tube sheet, a shell connecting the edge portions of said tube sheets and having a stepped portion disposed in opposition to the lower inclined tube sheet, tubes extending between the tube sheets and other tubes between the inclined lower tube sheet and the stepped portion of the connecting shell.

4. In apparatus of the character described, a calandria having oppositely disposed tube sheets with a wall connecting the same and provided with stepped portions opposed to and at different distances from one of the tube sheets and tubes of different lengths extending between said tube sheet and the stepped portions of said wall.

5. In apparatus of the character described, a calandria having oppositely disposed upper and lower tube sheets with a stepped wall connecting the same, tubes engaged between the tube sheets and other tubes engaged between one of the tube sheets and the stepped portions of the stepped wall.

6. In apparatus of the character described, a calandria comprising upper and lower tube sheets, one of greater diameter than the other, tubes extending between said sheets, a stepped wall connecting said tube sheets and tubes engaged between the stepped portion of said wall and one of the tube sheets.

7. In apparatus of the character described, a calandria comprising upper and lower tube sheets, one of greater diameter than the other, tubes extending between said sheets, a stepped down-take wall connecting said tube sheets and tubes engaged between the stepped portion of said down-take wall and one of the tube sheets.

8. In a vacuum pan or like apparatus, a calandria comprising an upper inclined tube sheet, a lower inclined tube sheet of greater diameter than the upper tube sheet, downwardly and outwardly inclined tubes extending between the upper tube sheet and the portion of the lower tube sheet which is of greater diameter than the upper tube sheet, a wall connecting the outer edges of

said tube sheets of different diameter and forming the outer wall of the calandria and a portion of the outer wall of the apparatus and a wall connecting the inner edges of the 5 tube sheets and forming a downtake.

9. The structure of claim 8 in which said outer wall of the calandria is substantially circular and is bulged outwardly to form a steam chamber entirely surrounding the 10 tubes and in which a drainage chamber with an outlet is provided in the lowermost portion of the calandria.

10. The structure of claim 8 in which the outer wall of the apparatus is of less diameter at the upper tube sheet and is of greater 15 diameter at points above and below said upper tube sheet.

11. The structure of claim 10 in which the lower tube sheet is disposed within the portion of the wall of greater diameter. 20

In witness whereof, I have hereunto set my hand this 12th day of April, 1920.

GODFREY ENGEL, SR.
